UNITED STATES PATENT OFFICE.

CHARLES HESSEY STUBLEY, OF LINCOLN ENGLAND, ASSIGNOR OF ONE-HALF TO
FRANKLIN WHITE, OF LINCOLN, ENGLAND.

DUST COLLECTING AND SEPARATING APPARATUS.

975,300.

Specification of Letters Patent.

Patented Nov. 8, 1910.

Application filed April 23, 1909. Serial No. 491,773.

To all whom it may concern:

Be it known that I, CHARLES HESSEY STUBLEY, subject of the King of Great Britain, residing at Lincoln, in the county of Lincoln, in the Kingdom of England, have invented certain new and useful Improvements in Dust Collecting and Separating Apparatus, of which the following is a specification.

This invention relates to apparatus to be carried by motor and the like vehicles for the purpose of collecting and discharging the dust raised by them. The apparatus consists of a chamber adapted to be carried by the vehicle and provided with collecting spouts or like devices adapted to be located in position behind the wheels of the vehicle or at any other point at which dust may be raised. The dust laden air is caused to travel up these spouts into the chamber and is there purified and the dust collected. This is effected by providing in the chamber a number of sleeves formed of a filtering material. Through the sides of these sleeves the air is caused to pass depositing the dust on the outside. One or both ends of each sleeve are open so that the air can pass freely therethrough, and escape to the atmosphere. The dust falls from the sleeves and is collected in a hopper or like receptacle arranged below.

The invention will be more fully described with reference to the accompanying drawings which illustrate diagrammatically a number of the forms of construction which may be adopted.

In these drawings:—Figure 1 is a transverse section of one form of the apparatus; Figs. 2 and 3 illustrate a second form, Fig. 2 being a side elevation and Fig. 3 a rear view partly in section; Fig. 4 is a longitudinal section through a filter sleeve showing the spring support therefor. In these views the course taken by the air is shown by arrows.

In the drawings and in the following description, similar reference letters are used in connection with the corresponding parts of the several forms of the apparatus.

Reference will first be made to the form of construction shown in Fig. 1. In this form the chamber *a* is of spiral or volute shape. The dust laden air is collected by means of the spouts *b* being drawn up by means of the fan or fans *c* located in the center of the chamber *a*. Before reaching

this central chamber the air first passes from the spouts *b* into the trunks *o* which connect at their upper ends with the chamber in which the fan is located. The air is driven in a spiral course from the center of the chamber *a* outward and thus encounters the filtering sleeves *d* which extend at intervals horizontally across the spiral passage. These sleeves *d* are connected at each end with a perforated plate *e* which forms the end wall *65* of the chamber *a*, and it will thus be seen that after passing through the filtering material into the sleeve the air is free to pass to the atmosphere through the opening at the ends, while the dust of course is retained *70* on the outside of the sleeves. The dust falls from the sleeves to the bottom of each part of the spiral and passes thence by way of the tubes *f* to the collecting hopper *g* below the chamber. This hopper is provided with *75* a valve *h* at its lower end which may be opened to deposit the dust when required. The trunks *o* are also provided at their lower ends with connections *y* (Fig. 1), with the hopper *g* so that any dust which is deposited *80* in the trunks may pass away therefrom.

In the arrangement illustrated in Fig. 1 the fan *c* is driven by means of a pulley actuated from a corresponding member attached to one of the wheels, but it will be *85* obvious that any other suitable connections may be used. Instead of arranging the spiral so as to lead the air from the center outward the opposite arrangement may be adopted. In this case a different arrangement of fan or fans will be necessary. This arrangement may, for instance, be similar to that employed in connection with the form of construction illustrated in the other figures of the drawings. Although the spiral *90* forms of chamber above described are particularly advantageous in certain cases, other shapes may also be adopted when desired. Examples of other shapes are given in the drawings.

In the arrangement shown in Figs. 2 and 3 the chamber *a* is of cylindrical form and the fans *c* are arranged to act as suction fans to draw the air through the apparatus and discharge it at *h*. In this case the perforated plates *m* which support the ends of the sleeves *d* are inclosed by a casing *n* which connects the filter chamber *a* with the two fan chambers. The spouts *b* in this case connect with the filter chamber by way of *100* *105* *110*

apertures *b'* (Fig. 3) in the front part of the cylindrical wall of this chamber. In other points this form of construction is substantially the same as that illustrated in Fig. 1.

5 In most cases it is found desirable to provide a central transverse partition *s* in the chamber *a* so as to prevent interference between the two currents of air which enter from opposite sides of the chamber.

10 In order to give additional support to the sleeves *d*, suitable springs or elastic bands, for instance longitudinal strip springs *t* (Figs. 1 and 4) may be used. These springs, as clearly shown in Fig. 4, extend

15 along the inside of the sleeves *d*, being attached with the sleeves to the end walls *e* and central partition *s* by clips *u* and *v* respectively, the spring being firmly secured to the central clip *v* but being free to slide

20 in the end clips *u*. They accordingly give support to the sleeves and also facilitate movement thereof under the influence of the vibration to which the chamber is subjected.

It will be obvious that filtering sleeves *d* need not necessarily be circular in cross section, but may be of any convenient shape.

The fans may be driven from any suitable part of the vehicle as previously mentioned, or by means of a small motor, turbine or the like operated by the exhaust from the engine.

It will be understood that the forms of construction illustrated in the drawings and above described are simply given by way of illustration and that the invention is not restricted to these exact forms.

I declare that what I claim is:—

1. A portable dust collecting and separating apparatus comprising a filtering chamber having a pair of approximately vertical oppositely disposed walls provided with perforations, filtering sleeves extending approximately horizontally between said walls their ends coinciding with the perforations and the sleeves being supported by said walls, means for causing air to pass into said chamber around the outside of said sleeves, the purified air escaping from the ends of the sleeves and the dust being caught on the outside thereof, means located below said sleeves for collecting the dust falling therefrom.

2. A portable dust collecting and separating apparatus comprising a filtering chamber having a pair of oppositely disposed walls provided with apertures, filtering

sleeves extending approximately horizontally across said chamber, means forming part of the walls of said chamber for supporting said sleeves at their ends which coincide in position with apertures in said walls, spring means for supporting said members at intermediate points, means for causing the air to pass into the chamber around the outside of said sleeves, to pass through said sleeves and to escape from the ends thereof and the dust being caught on the outside thereof, means located below said sleeves for collecting the dust falling therefrom.

3. A portable dust collecting and separating apparatus comprising a filtering chamber, filtering sleeves extending approximately horizontally across said chamber and supported at their ends by the walls thereof, means for causing air to enter said chamber at both ends thereof and to pass through the filtering sleeves, and a transverse partition member arranged centrally in said chamber so as to prevent interference between the two streams of air.

4. A portable dust collecting and separating apparatus comprising a filter chamber, filtering sleeves extending approximately horizontally across said chamber and supported at their ends by the walls thereof, means for causing air to enter said chamber at both ends thereof and to pass through the filtering sleeves, a transverse partition member arranged centrally in said chamber, and strip springs attached to said sleeves and supported by said partition and the walls of the chamber.

5. A portable dust collecting and separating apparatus comprising a filtering chamber forming a spiral passage for dust laden air, means for causing air to flow along said passage, filtering sleeves arranged horizontally across said passage and having open ends so that the filtered air can escape while the dust is retained on the outsides of the sleeves, a dust collecting hopper arranged below the filtering chamber, and ducts leading from the lower part of each curve of the spiral passage to said hopper.

In witness whereof, I have hereunto signed my name this 7th day of April 1909, in the presence of two subscribing witnesses.

CHARLES HESSEY STUBLEY.
